UNITED STATES PATENT OFFICE.

JOHN ULRICH AND CHARLES LETTERI, OF COLUMBUS, OHIO.

SAFETY DEVICE FOR STEAM-BOILERS.

No. 893,036.

Specification of Letters Patent.

Patented July 14, 1908.

Application filed September 18, 1907. Serial No. 398,427.

To all whom it may concern:

Be it known that we, JOHN ULRICH and CHARLES LETTERI, citizens of the United States, residing at Columbus, in the county 5 of Franklin and State of Ohio, have invented certain new and useful Improvements in Safety Devices for Steam-Boilers, of which the following is a specification.

Our invention relates to safety devices for 10 steam boilers and has for its object the provision of a device of this character constructed in such manner that if the water in the boiler drops below a predetermined point, a valve will be automatically operated to admit 15 steam from the boiler to the fire box to smother the fire.

Further objects and advantages of the invention will be set forth in the detailed description which now follows.

20 In the accompanying drawing: Figure 1 is a vertical sectional view of the rear portion of a locomotive boiler illustrating the manner of applying this improved safety device thereto, Fig. 2 is a vertical sectional view of 25 the improved safety device itself, and, Fig. 3 is a horizontal section upon line x—x of Fig. 2.

Like numerals designate corresponding parts in all of the figures of the drawing.

Referring to the drawing, the numeral 5 30 designates the rear portion of a locomotive boiler. A pipe 6 which opens into the fire box through the crown sheet of the boiler is connected by an L 7 with a pipe 8. The pipe 8 is in turn connected by an L 9 with a pipe 35 10, and this latter pipe is threaded as at 11 into the cap plate 12 of a casing 13. This casing has a reduced portion 14 formed upon its lower end and a T 15 is threaded upon this 40 reduced portion. A blow-off cock or valve 16 is threaded into this T and a pipe 17 connects this T with the water space of the boiler at any desired point.

A bracket 18 encircles the casing 13 at its 45 upper portion and provides means for securing the casing to the front of the boiler. A gage or water glass 19 is connected to the casing as at 20 and 20' and provides means for indicating the height of water in the boiler in the usual manner. A float 21 is 50 disposed within the casing 13 and this float has a stem 22 threaded therein, said stem being held against turning with relation to the float, by a lock nut 23. The upper end of the stem is formed into a needle valve 24 55 which is adapted to contact with a valve seat 25 formed in a pendent portion 26 which is

carried by a plate 27. This plate has an outstanding annular flange 28 which rests upon a shoulder 29 of the casing 13, the plate and the pendent portion being securely held in 60 position when the cap plate 12 is fastened in position by nuts 30 which are screwed upon bolts 31. The pendent portion 26 is cut out as at 32 for the reception of a piston 33. A piston rod 34 connected to this piston forms 65 the stem of a valve 35. A port 36 leads from the lower portion of the chamber 32 to a relief valve 37. A plug 38 in which the piston rod 34 is slidably disposed, closes the upper portion of the chamber 32. A port 39 70 formed in this plug is in communication with the pipe 10 through a port 40. The valve 35 normally closes the port 39, said port 39 being in communication by ports 41 and 42 (see Fig. 3) with the interior of the casing 13. 75

The operation of the device is as follows: As long as water is present in the boiler to such a height as to lift the float 21 to such position as to maintain the valve 24 in engagement with its seat 25, the parts will all 80 be in the position illustrated in Fig. 2. If, however, the water in the boiler should fall to such a level that the float is permitted to descend, steam will enter through the port 43 to the chamber 32, the relief valve 37 being 85 normally closed. The steam acts upon the piston 33 to elevate said piston and consequently to lift the valve 35 from its seat. The steam and water may then flow through the ports 42, 41, 39 and 40 to pipe 10 and 90 from pipe 10 to the fire box through the connections described, where it will smother the fire sufficiently to prevent an explosion until the engineer or fireman can introduce more water to the boiler. When upon the intro- 95 duction of water to the boiler, the float is again lifted and the flow of steam to the chamber 32 is cut off, the piston would not immediately descend to close the port 39 and thereby cut off the flow of steam to the fire 100 box if the relief valve 37 were not provided. When this relief valve is open, all pressure under the piston is relieved and the valve and piston will drop by gravity to cut off the flow of steam through the port 39. If this 105 relief valve were not provided, the expansion of the steam when confined in the lower portion of the chamber 32 would hold the piston in an elevated position even after the float had been lifted by the introduction of water 110 to the boiler. By providing this relief valve, the flow of steam to the fire box may be

stopped just as soon as a sufficient quantity of water has been permitted to enter the boiler. Since the flow of steam to the fire box is downwardly past the valve 35, it will 5 of course be understood that this will also tend to close said valve.

From the foregoing description, it will be seen that simple and efficient means are herein provided for accomplishing the objects of 10 the invention, but while the elements shown and described are well adapted to serve the purposes for which they are intended, it is to be understood that the invention is not limited to the precise construction set forth, but 15 includes within its purview such changes as may be made within the scope of the appended claims.

What we claim, is:

1. In a device of the character described, 20 the combination with a steam boiler, of a casing, a pipe leading from said steam boiler to said casing, a pipe leading from said casing to the fire box of the boiler, and a valve mechanism located within said casing and adapted when the water in the boiler drops to a predetermined level to admit steam at 25 boiler pressure to the pipe leading to the fire box.
2. In a device of the character described, 30 the combination with a steam boiler, of a casing, a pipe leading from said steam boiler to said casing, a pipe leading from said casing to the fire box of the boiler, and a float controlled valve mechanism located within said 35 casing and adapted when the water in the

boiler drops to a predetermined level to admit steam at boiler pressure to the pipe leading to the fire box.

3. In a device of the character described, 40 the combination with a steam boiler, of a casing, a pipe leading from said steam boiler to said casing, a pipe leading from said casing to the fire box of the boiler, a valve located within said casing and adapted to control the flow of steam from the interior of said casing to the fire box, a piston to which said valve is connected, a float, and a valve connected to said float, said latter valve being adapted to control the flow of steam to said piston. 45

4. In a device of the character described, 50 the combination with a steam boiler, of a casing, a pipe leading from said steam boiler to said casing, a pipe leading from said casing to the fire box of the boiler, a valve located within said casing and adapted to control the 55 flow of steam from the interior of said casing to the fire box, a piston to which said valve is connected, a float, a valve connected to said float, said latter valve being adapted to control the flow of steam to said piston, a chamber in which said piston is slidably disposed, 60 a port leading from said chamber, and a relief valve adapted to open or close said port.

In testimony whereof we affix our signatures in presence of two witnesses.

JOHN ULRICH.
CHARLES LETTERI.
